RESISTANCE CONTROLLER

Application filed June 7, 1929. Serial No. 369,096.

This invention relates to controllers for electric circuits and more particularly to the control of resistances for gradual inclusion in and exclusion from such circuits. The invention is particularly applicable to the control of dynamo electric machines by means of resistances in their armature circuits.

In certain motor installations, for instance in drives for fans and blowers, it is desirable to provide a large number of speed points for the motors. The ordinary arrangement of resistances and controllers for such an installation would require an excessive number of resistance sections and a correspondingly large number of contacts on the controller, resulting in a large controller, the cost of which may be prohibitive. Furthermore, when the motor to be controlled is of large capacity, the contacts on the controller and the wires connecting the controller and resistance sections have to be of such large capacity, that the controller will be prohibitive in size and difficult of manipulation, and the accommodation of the connecting wires will be another serious problem.

If the controller is of the type where the resistance is commutated by magnetic switches, which in turn are controlled by a master controller, the number and size of the switches required to obtain a large number of resistance steps may be prohibitive.

Moreover such large magnetic switches have a highly inductive magnet circuit, which results in rapid wear due to burning of the contacts of the master controller.

If a system of control in which a limited number of resistance sections and corresponding switches, is employed, the various sections may be cut in and out of circuit in various combinations, thereby yielding a relatively greater number of possible speed points. But this system has the disadvantage that the opening and closing of the respective magnet operating circuits, when changing from one combination to another, does not take place coincidently, so that undesired intermediate combinations result which interfere with the smooth operation of the motor.

An object of my invention is to provide a controller in which the resistance commuta-

tion from step to step is accomplished substantially instantaneously.

Another object is the elimination of sparking at the master controller due to the commutation of the resistances or switches. 55

Another object is to provide a controller of the aforescribed kind in which undesired resistance stepping during commutation is avoided.

Another object is to provide a controller in 60 which the speed of change-over between successive points of the controller is independent of the speed with which the master is moved between successive points.

Further objects and advantages of the invention will hereinafter appear. 65

The single figure of the accompanying drawing illustrates schematically and diagrammatically one embodiment of my invention, which will now be described, it being 70 understood, that the invention is susceptible of embodiment in other forms without departing from the scope of the appended claim.

Referring to the drawing, A represents the 75 armature and F the series field of a direct current motor, which is supplied with energy from the lines L¹ and L². The current to the motor is controlled by means of resistance steps R¹, R², R³ and R⁴. 80

The resistances R¹ to R⁴ are so proportioned, that the ratio of their ohmic values represents a geometric progression. For example, resistance R¹ may be one ohm, resistance R² two ohms, resistance R³ four ohms 85 and resistance R⁴ eight ohms. By properly combining the resistances as will be described later, a value from zero to 15 ohms can thus be obtained, the succeeding values differing by one ohm. 90

The motor circuit is closed by means of the main switch Ma, which is equipped with an electromagnet M, the latter when energized causing closure of the switch. The resistances R¹ to R⁴ are controlled by the respective resistance commutating electromagnetic switches 1a to 4a, the switches being actuated by electromagnets 1 to 4 respectively. The relay C, having the electromagnetic actuating winding Ca, the normally open 95 100

contacts C^1 , C^2 , C^4 and C^6 and the normally closed contacts C^3 , C^5 and C^7 , is provided for the control of the electromagnetic switches aforescribed, while the drum controller D, 5 which is equipped with the stationary contact fingers D^1 to D^{10} inclusive, provides for the adjustment of the resistor to the desired resistance value.

The controller functions in the following 10 manner:

If the lines L^1 , L^2 are energized and it is desired to start the motor, the drum controller is moved to its first operating position, thereby completing a circuit from line L^1 to 15 drum finger D^3 , drum finger D^1 , through magnet winding M, to line L^2 . This causes closure of the switch Ma , and the motor is connected across the lines in series with the resistances R^1 to R^4 inclusive. Closure of 20 magnet switch M also closes the normally open auxiliary contact Mb , so that a second path is established from drum finger D^2 , through contact Mb , through the magnet winding M to line L^2 . Thus upon movement 25 of the drum controller to the second position the magnet winding M is maintained through the contact Mb , and upon failure of voltage in this or succeeding positions the main switch Ma is opened and cannot close again 30 until the drum is returned to the first operating position, where the maximum resistance is inserted in the motor circuit, and thus an excessive inrush current is avoided.

The motor is started at the first operating 35 point with a total resistance of 15 ohms in series. If it is desired to increase the speed of the motor, the control is moved to the second operating point. This causes energization of the magnet Ca and the closure of 40 contact C^1 . The electro-magnet 1 is energized, which causes closure of the contact $1a$ and short circuiting of the resistance R^1 . The total resistance in series with the motor is thus reduced by one ohm to a value of 45 ohms.

Movement of the controller to the third operating position causes re-opening of the magnet Ca and thus deenergization of the switch 1, but contact has been made with the 50 drum finger D^6 , and since the deenergization of Ca causes closure of contact C^2 , the electro-magnet 2 is energized, causing closure of switch $2a$ and short circuiting of the resistance R^2 , so that the total resistance in series 55 with the motor is now 13 ohms.

Further movement of the controller to the fourth operating position causes reenergization of Ca and thus reclosure of switch $1a$, while the magnet 2 of switch $2a$ is maintained through contact finger D^5 and contact C^2 of relay C, which latter contact is closed by the reenergization of the magnet Ca . Thus the total resistance in series with the motor is reduced to 12 ohms.

Further movement of the drum controller

to the succeeding positions will cause the energization of the switches 2 to 4 in such manner and combination, that with each successive step the total resistance in series with the motor is decreased by one ohm, and a reversal of the drum controller will cause similar increase in the resistance.

It is apparent, that the only contact points on the drum controller which have to open and close circuits under current are the fingers D^1 and D^4 , the former controlling the main switch when the motor is started and the latter controlling the relay Ca , which is of relatively low current capacity, and the resulting sparking therefore is negligible. 70 The wear on this finger and the corresponding segments is therefore slight. The circuits of the other switches which are of high capacity and the magnets of which therefore are highly inductive, is made and broken 75 on the contacts C^1 to C^7 inclusive of the relay C and not on the drum controller. As these contacts open and close the circuits of the electromagnets rapidly, the resulting 80 arcing and wear are reduced to considerably 85 lower values than would be realized, if the circuits were made and broken on the relatively slow moving drum.

It will thus be seen that by this arrangement I am able to obtain a relatively large 90 number of operating points for the controller with a small number of resistance steps and a small number of controlling electromagnets, while at the same time I have reduced 95 the wear on the controller due to arcing. As 100 the magnet switches can be mounted near the resistor and the motor, while the master drum may be mounted in any convenient place, I have reduced the number and length 105 of heavy conductors for the controller to a minimum, while the number of small control wires, which have to be provided for between the master drum and the electromagnetic switches at the motor, is also reduced 110 to a minimum.

What I claim as new and desire to secure by Letters Patent is:

In combination, a plurality of resistance sections to be included in or excluded from a circuit, said resistance sections being so proportioned, that the ohmic value of each section is equal to substantially twice the ohmic value of the immediately preceding section, and means for commutating said sections in predetermined sequence, whereby resistance gradations of equal value corresponding in 115 number to twice the ratio of ohmic values of the last section to the first section may be obtained, said means comprising a plurality of electromagnetically operable switches each adapted to control one of said resistance sections, an electroresponsive relay having contacts in circuit with the operating windings 120 of said plurality of electromagnetically operable switches and a master switch having 125 130

contacts in circuit with the operating windings of said plurality of electromagnetically operable switches and having additional contacts in circuit with the operating winding of said relay, said master switch contacts affording selection of said electromagnetically operable switches for different commutations of said resistance sections and said relay being energized and deenergized by said master

switch according to the position of the latter to execute the selections made by said master switch in respect of said electromagnetically operable switches and to render transitions substantially instantaneous. 70

In witness whereof, I have hereunto subscribed my name.

EDWIN W. SEEGER.
